SWING FRAME GRINDER

Charles E. Hite, Philadelphia, Pa., assignor to
Albert P. de Sanno, Jr., Phoenixville, Pa.

Application October 24, 1944, Serial No. 560,137

5 Claims.

(Cl. 51—59)

My present invention relates to swing frame grinders and more particularly to a swing frame grinding machine having a release of the handle bars to downward movement when the bars are subjected to unduly high down-pressure and in part the invention may be considered a development of the subject matter disclosed and claimed in my U. S. Patent No. 2,290,611, granted October 12, 1941, and entitled Swing frame grinder.

An object of the invention is to mechanically limit the down-pressure transmissible by an operator of a swing frame grinding machine to the grinding wheel and piece of work being ground, thereby preventing an operator from applying wheel pressures dangerously or undesirably high.

A further purpose is to reduce wheel hazard, maintain continuing cutting effectiveness and wheel strength, lengthen wheel life and to reduce the over-all cost of swing frame grinding operations.

A further object is to hinge the handle bars of a swing frame grinder to the protection hood of the wheel unit and to resiliently support the handle bars in their position of use except when subjected to an abnormally high down-pressure by the operator.

A further object is to have the handle bars sink out of their position of use when subjected to abnormally high down pressure, thereby preventing grinding with unduly high pressures upon the handle bars.

A further object is to materially lessen shock and vibration, that between the wheel and work and that transmitted through the handle bars to the operator, using resilience in the support of the handle bars from the hood and preferably also resilience in the support of the hood from the frame.

A further object is to provide the handle bars with a narrow range of upward and downward movement under a corresponding range of rising and falling down-pressures applied by the operator and with a release of a resilient support when the down-pressure applied to the handle bars rises to a selected limit.

A further object is to provide the hinged handle bars with two resilient supports against downward movement from their position of use, one support with complete release at the end of a short downward movement of the handle bars and the other support with continuing retraction throughout the downward swing of the handle bars.

A further object is optionally to omit one or other of the two supports, the use of either sup-

port without the other having particular advantages though normally less advantageous than the cooperating use of both.

As to the train of evils intended to be cured through the present invention, the application by the grinding operators of excessive pressure upon the handle bars has increased operating stresses and strains within wheels and power consumption in driving them and more serious than this has resulted in unduly heating the work and the wheels.

The undue heating of the wheels and work has caused the wheel faces to glaze with metal from the work and has also weakened the wheels, lessened the intrinsic strength of the bonding material holding together their abrasive grains.

The weakening of the wheels from overheating and the increased stresses and strains within the wheels from too high pressures has caused wheels to fly apart in service, making the operation, particularly of heavy duty wheels, extremely hazardous.

And the glazing of the cutting faces has made the cutting ineffective, making it necessary to dress wheel faces when without such unnecessary glazing the dressing operation with the resultant loss of wheel material and of the effective use of the wheel could have been avoided.

Further objects will appear in the specification and in the claims.

I have elected to illustrate two only of the different forms of my invention, illustrating forms, however, that practical and efficient in operation and which well illustrate the principles involved.

The figures of the drawing are intended to be conventional and to bring out more clearly the principles involved are in great measure diagrammatic.

Figures 1 and 2 are side elevations of somewhat different embodiments of the invention, with the views intended to be alike except with respect to a distinguishing feature.

Figure 3 is a bottom plan fragment.

Like numerals refer to like parts in all figures. Describing in illustration and not in limitation and referring to the drawing:

In Figure 1, a conventional frame 5 supports at one end 6 the protection hood 7 of a wheel unit and toward the other end carries a usual or suitable motor 8.

Intermediate the motor and hood, a sleeve 9, adjustable at 10 along the frame, presents an eye 11 to the lower end of a swing element 12 intended for any usual or suitable swing support.

The hood 7 carries and forms part of the wheel

unit. The wheel 13 is shown presented to a work piece 14, and driven by belt 15 from the motor 8, the pulley 16 of the motor driving by belt connection the pulley 17 on the shaft 18 of the wheel 13.

The wheel 13, shaft 18 and pulley 17 are rotatably supported by the hood 7 in usual or suitable bearings not shown. As thus far described the hood and wheel unit is in usual prior art.

In prior practice, the protection hood has been welded at 6 to the end of the frame 5, with the inner end of the operating handle or handle bars welded or rigidly fastened to the opposite side of the hood, as at 19.

To both limit pressure transmissible by the operator through the handle bars and to shield the operator from the hood vibration, I weld or otherwise fasten conventional handle bars 20 to opposite sides of a rocker 21, pivoting the rocker at 22 in opposing lugs 23 of the hood 7.

The rocker is provided with an upward arm 24 and an opposing upward arm 25 of the hood carries springs 26 and 27 that engage the arm 24 and normally retract it against a stop lug 28 from the hood.

The spring 26 is a tension spring, preferably a spring of pre-set tension, that is, a spring with the successive turns of the spring in contact, pressing together until the initial or pre-set tension is overcome when the rocker begins to be pulled away from the high position at which it presents the handle bars 20 in position for convenient use by the operator.

The spring 27 is a flat spring with a latching head having inner and outer reversely sloping surfaces 29 and 30 to engage the top of the rocker arm 24.

The spring 27 is held to its duty between opposing washers 31 and 32 by a stud 33 into the flat top of the arm 25. The washers are slotted at 34 in direction of the spring length to permit adjustment of the spring strength by shifting the washers or either washer.

In normal high position of the rocker and handle bars the spring 27 presents its bevel surface 29 against the top of the rocker, resiliently resisting any downward deflection of the handle bars until any such deflection carries the top of the rocker beyond the slope 29.

When the handle bars are raised from a low position to their high position of normal operation, the outer sloping surface 30 slides along the top of the rocker arm, lifting the spring 27 for its latching engagement between the surface 29 and the top of the rocker.

When an operator applies excessive downward pressure to the handle bars, moving them downward from their high position, they are given a momentary additional urge downward by the flat spring 27 during its engagement at the surface 30 with the top of the arm 24.

The spring 27 is intended to comprise any suitable spring latch between the rocker handle bars in their high position and the hood, holding the handle bars in their high position for a short up-and-down range of movement of the bars, releasing the bars when the limit of short downward movement is exceeded (because of excessive down-pressure applied by an operator), and letting the bars then drop except as they may be desirably under a retracting upward support of the spring 26.

The spring 26 is intended to comprise any suitable spring connection between the rocker handle bars and the hood providing the bars with

resilient upward support throughout a range of up-and-down movement of the bars.

The springs 26 and 27 are intended to be selected and placed for their combined strength to hold the rocker handle bars in their high position against normal operating down pressure upon the bars and to permit the handle bars to move downward if an operator applies to them excessive down pressure.

Some of the advantages may be obtained by the use of either spring without the other and when this is done the strength and placement of the used spring should hold the handle bars in their high position against normal operating down pressure upon the bars and permit the handle bars to move downward under excessive pressure upon the bars.

An important object of the springs 26 and 27 where both are used, or of either spring used without the other, is to absorb or cushion hood vibration otherwise transmitted through the handle bars to the operator.

When the hood has given rigid support to the handle bars, in accord with frequent practice of the prior art, the heavy vibration during heavy duty service, from the hood through the handles to the operator, has been a serious characteristic of this type of grinder, both in the effects on the operator from the heavy shaking given him during service and in the effects on the wheel in that the shocks on the operator transmit back to the wheel.

When the hood has carried the wheel unit and handle bars and been itself carried by the frame with a rigid direct connection between the frame and hood, as by welding the hood at 6 to the end of the frame, in accord with frequent practice of the prior art, the heavy vibration transmitted from the hood to the frame and through the frame to the driving mechanism has also been a serious characteristic of this typegrinder, subjecting the driving mechanism to heavy shaking with corresponding shocks delivered to the wheel and work because of the inertia of the frame and driving mechanism, and another important object of my invention is to correct this condition by the insertion of resilience in the supporting connection between the hood and frame.

In Figure 2, the parts intended to be optionally the same as in Figure 1 are given corresponding numerals primed and their description, given for Figure 1, is not repeated for Figure 2.

In Figure 2 I provide resilience in the supporting connection between the frame and hood and show this conventionally as a flat spring 35 of size and resilient characteristics to suit the intended service.

The spring 35 is illustrated as rigidly fastened, as by welding, at one end to the frame 5' and at the other end to the hood 7'.

In view of my invention and disclosure, variations and modifications will doubtless become evident to others skilled in the art and I claim all such in so far as they may fall within the reasonable spirit and scope of the invention.

Having thus described my invention what I claim as new and desire to secure by Letters Patent is:

1. A swing frame grinder having an operating handle, a grinding wheel, a hood carrying the handle and mounting the wheel, a swing frame supporting the hood in a position longitudinally intermediate the handle and frame and the structure characterized by a hinge between the handle and hood adapting the handle to down-

ward deflection from its position of normal operation and a spring upwardly retracting the handle to its position of normal operation and during grinding resiliently cushioning the handle from vibration of the hood.

2. A swing frame grinder having an operating handle, a grinding wheel, a hood carrying the handle and mounting the wheel, a swing frame supporting the hood in a position longitudinally intermediate the handle and frame and the structure characterized by a hinge between the handle and hood adapting the handle to downward deflection from its position of normal operation and a spring upwardly retracting the handle to its position of normal operation and additionally characterized by a spring connection between the hood and frame whereby during grinding the hood is resiliently cushioned from vibration of the frame.

3. A swing frame grinder having a swing frame, an operating handle, a grinding wheel, a hood mounting the wheel, a hinge between the handle and hood adapting the handle to downward deflection from its position of normal operation and a spring resiliently retracting the handle against normal down-pressure applied by an operator and

of resilience to limit the down pressure that an operator may transmit through the handle and hood to the wheel and work.

4. A swing frame grinder having an operating handle, a grinding wheel, a hood supporting the handle and mounting the wheel, a swing-frame supporting the hood and the structure characterized by a hinge between the handle and hood adapting the handle to downward deflection from its position of normal operation and by a latch latching the handle from downward deflection during normal operation and releasing under abnormally high pressure applied to the handle.

5. A swing frame grinder having an operating handle, a grinding wheel, a hood supporting the handle and mounting the wheel, a swing-frame supporting the hood and the structure characterized by a hinge between the handle and hood adapting the handle to downward deflection from its position of normal operation, by a spring upwardly retracting the handle and by a latch latching the handle from downward deflection during normal operation and releasing under abnormally high pressure applied to the handle.
